UNITED STATES PATENT OFFICE.

ANTHONY A. BARBERA, OF PHILADELPHIA, PENNSYLVANIA.

ELECTRIC SIGNAL SYSTEM.

No. 897,702.

Specification of Letters Patent.

Patented Sept. 1, 1908.

Application filed February 28, 1908. Serial No. 418,220.

To all whom it may concern:

Be it known that I, ANTHONY A. BARBERA, a citizen of the United States, and a resident of Philadelphia, in the county of Philadelphia and State of Pennsylvania, have invented a new and Improved Electric Signal System, of which the following is a full, clear, and exact description.

My invention relates to electric signal systems, my more particular object being to produce such a system under the immediate control of a towerman and used in connection with a movable semaphore arm for indicating to the engineer of a moving locomotive the position of the semaphore arm, by flashing appropriate lamps or energizing an appropriate alarm in the cab of a locomotive.

My invention further relates to means whereby, in case the semaphore arm is disabled, the towerman may transmit to the engineer appropriate signals equivalent to those which would be transmitted to him if the semaphore arm were in proper working order.

My invention relates still further to means whereby the electrical connections may be tested by the towerman in order to ascertain their condition.

Reference is to be had to the accompanying drawings forming a part of this specification, in which similar characters of reference indicate corresponding parts in all the figures.

Figure 1 is a diagram of the wiring used, this wiring extending from the semaphore arm to the tower-house, and also to certain contact rails which are brought, by movements of the locomotive, into electrical communication with the wiring used upon said locomotive; Fig. 2 is a section, partly diagrammatic, showing the location of colored lamps and an auditory alarm, all carried by the cab and energized electrically by appropriate contact mechanism partly under control of movements of the locomotive; and Fig. 3 is a fragmentary section showing the movable semaphore arm and the contact mechanism controllable by it, for the purpose of completing and breaking certain electric circuits controlling the lamps and other alarm members used in the tower-house and locomotive cab.

Mounted upon a post 4 is a semaphore arm 5 adapted, as is usual with semaphore arms, to turn within certain limits. This arm is

mounted rigidly upon a stub shaft 6 extending directly through the post 4 and into a casing 7 disposed upon the side thereof opposite the semaphore arm 5. A disk 8 of insulating material, preferably fiber, is mounted within the casing 7 and thus protected from the weather. Sunken within the disk 8 are stationary contact members 9, 10, 11, 12, all of arcuate form, the contact member 9 being considerably longer than the contact members 10, 11, 12. A contact finger 8^a is mounted rigidly upon the stub shaft 6 and turns therewith whenever the semaphore arm 5 is turned. One end of the contact finger 8^a always rests upon the contact member 9, and the other end of the contact finger may engage any one of the contact members 10, 11, 12, though it normally rests upon the contact member 10. The contact finger 8^a is made of spring metal so as to make a firm engagement with the contact members.

Connected with the contact members 10, 11, 12 are wires 13, 14, 15, these latter being connected with wires 16, 17, 18. Short wires 19, 20, 21 are connected with the wires 16, 17, 18, and with lamps 22, 23, 24. These lamps are of different colors, the lamp 22 being white, 23 being green and 24 being red. Connected also with these lamps are short wires 25, 26, 27, these wires being connected by wires 28, 29 with a contact button 30 of a switch 31, which is connected by a wire 32 with a battery 33. Connected with the wires 16, 17 and 18 are short wires 34, 35, 36, leading respectively to contact buttons 37, 38, 39, which are provided for a switch 40. This switch is connected by wires 41, 41^a with the battery 33. A wire 42 is connected with the wires 41, 41^a and leads to the contact member 9 of the disk 8.

A switch tower is shown at 43 and is occupied by the operator, who controls practically the entire system. At 44 is shown the cab of a traveling locomotive. Carried by the locomotive are a white lamp 45, a green lamp 46, a red lamp 47 and a buzzer 48 or other auditory alarm. Wires 49, 50 connect this member with the red lamp 47. Wires 51, 52, 53 are connected respectively with the lamps 47, 46, 45. Wires 55, 56 are connected by a wire 57 with the green lamp 46. A wire 58 connects the red lamp 47 with the wires 49, 62^a. Contact shoes 59, 60, 61 carried by the locomotive are connected respectively with the wires 51, 52, 53, and disposed partially with

in the path of these shoes are stationary contact rails 62, 63, 64. Another rail 65 is disposed partially within the path of a contact shoe 63^a carried by the locomotive, and this 5 shoe is connected by a wire 62^a with the wires 49, 55, 58. A wire 66 connects the contact rail 65 with the contact button 30.

The semaphore arm 5 normally hangs vertically downward, as indicated in Fig. 1. It 10 may be raised to different angles, however, and as is usual in semaphore arms, adapted to assume positions indicating safety, caution and danger, these three positions being represented by the three colors of the lamps and 15 by the three contact members 10, 11, 12.

The operation of my device is as follows: We will assume that all of the parts are in their normal positions, and that a locomotive is approaching. The arm 5 hangs vertically downward, as above explained. The 20 switch 40 is open and the switch 31 is closed. The battery circuit is open. When, however, the locomotive reaches such position that the contact shoes 61, 60, 59, 63^a engage 25 respectively the contact rails 64, 63, 62, 65, a circuit is completed as follows: battery 33, wire 41^a, wire 42, contact member 9, contact finger 8^a, contact member 10, wire 13, from whence the current divides, a portion passing 30 through wire 16, wire 19, white lamp 22, wire 25, wire 29, contact button 30, switch 31, and wire 32 back to battery 33. Another portion of the current from the wire 16 pursues the following path, to wit: contact rail 35 34, contact shoe 61, wire 53, white lamp 45 in locomotive cab, wire 56, wire 55, wire 62^a, contact shoe 63^a, contact rail 65, wire 66, contact button 30, switch 31 and wire 32 back to battery 33. In other words, from 40 the wire 16 two portions of the current pass in parallel through the lamps 45 and 22, causing them to light up and apprise the towerman that the locomotive is coming, as well as apprising the engineer that he is approaching the tower. Suppose, however, that the parts are in normal position, as 45 above described, and that the towerman wishes to give to the locomotive engineer the warning commonly known as "danger". To 50 do this the towerman, in any appropriate manner, turns the semaphore-arm 5 so that the contact-finger 8^a engages the contact member 12, as well as the contact member 9. The locomotive having arrived at the point 55 where its contact shoe can engage the contact rails, as above described, the following circuits are completed: battery 33, wire 41^a, wire 42, contact member 9, contact finger 8^a, contact member 12 to wire 15; thence the 60 current divides, a portion passing through wires 18, 21, red lamp 24, wires 27, 28, 29, contact button 30, switch 31 and wire 32 to battery 33. Another portion of this current passes from the wire 15 to contact rail 62, 65 contact shoe 59, wire 51, red lamp 47, wire

58, wire 55, wire 62^a, contact shoe 63^a, contact rail 65, wire 66, contact button 30, switch 31, wire 32 to battery 33.

From the wires 51, 62^a a shunt circuit is at the same time completed through the buzzer 70 48, so that the buzzer sounds whenever the red lamps 24, 47 are thus energized. If, however, the semaphore-arm 5 be moved only so far upward that the contact finger 8^a reaches from contact member 9 to contact 75 member 11, the following circuits are completed: battery 33, wire 41^a, wire 42, contact member 9, contact finger 8^a, contact member 11, to wire 14; thence the current divides, a portion passing through wire 17, 80 wire 20, green lamp 23, wires 26, 28, 29, contact button 30, switch 31, wire 32 to battery 33; another portion of the current passing from the wire 14 to contact rail 63, contact 85 shoe 60, wire 52, green lamp 46 of locomotive, wires 57, 55, wire 62^a, contact shoe 63^a, contact rail 65, wire 66, contact button 30, switch 31, wire 32 back to battery 33. This circuit does not energize the buzzer 48. It 90 will thus be noted that the position of the 95 semaphore-arm 5 causes the simultaneous lighting of two lamps, one in the tower and one within the locomotive cab, the color of the lights thus made indicating both to the operator in the tower and the engineer in the 95 locomotive cab the position of the semaphore-arm 5. Suppose, however, that for any reason the semaphore-arm 5 is out of order and can not be relied upon to control the signals. The operator, by aid of the switch 100 40, can complete circuits through the lamps. For instance, by turning the switch-arm 40 into engagement with the contact button 37 the following circuit is completed: battery 105 33, wire 41^a, wire 41, switch arm 40, contact button 37, wire 34, wire 19, white lamp 22, wire 25, wire 29, contact button 30, switch arm 31, wire 32 to battery 33. This circuit lights the lamp 22. A portion of the current, however, upon arriving at the wire 34, 110 instead of passing upwardly into wire 19 passes into wire 16, rail 64, contact shoe 61, wire 53, white lamp 45, wire 56, wire 55, wire 62^a, contact shoe 63^a, contact rail 65, wire 66, switch arm 31, and wire 32 back to 115 battery 33. The lamp 45 in the locomotive cab is thus lighted.

The switch-arm 40 being turned into engagement with the contact button 38, the following circuit is completed: battery 33, wire 120 41^a, wire 41, switch arm 40, contact member 38, wires 35, 20, green lamp 23, wires 26, 28, 29, contact button 30, switch arm 31, wire 32 back to battery 33. This lights the green lamp 23. A portion of the current, however, upon arriving at the wire 35 in the circuit just traced, pursues the following path: wire 17, contact rail 63, contact shoe 60, wire 52, green lamp 46, wire 57, wire 55, wire 62^a (so as to light the green lamp), con- 130

tact shoe 63^a, contact rail 65, wire 66, contact button 30, contact arm 31 and wire 32 back to battery 33. The engineer can now see that he must proceed cautiously.

5 Suppose, next, that the operator in the tower turns the switch arm 40 into engagement with contact button 39. The following circuit is thus completed: battery 33, wire 41^a, wire 41, switch arm 40, contact member 39, wire 36, wire 21, red lamp 24, wires 27, 28, 29, contact button 30, switch arm 31, wire 32 to battery 33, this circuit thus lighting the red lamp 24. A portion of the current, however, upon arriving at the 15 wire 36 in the circuit above traced, passes through the wire 18 to contact rail 62, thence to contact shoe 59, wire 51, red lamp 47, wire 58, wire 62^a, contact shoe 63^a, contact rail 65, wire 66, contact member 30, contact 20 arm 31, wire 32, to battery 33, this portion of the current lighting the red light 47. A portion of the current in the circuit just traced, upon arriving at the wire 51, is diverted through a shunt consisting of wire 50, 25 buzzer 48 and wire 49 to wire 62^a, thus energizing the buzzer and thoroughly arousing the engineer.

From the above it may be seen that the system may be operated either automatically, in the sense that the signals are controlled by the position of the semaphore-arm 5, or hand-controlled, in the sense that the signals are under control of the switch-arm 40. In order to throw the entire system out of action, the switch-arm 31 is moved to the right.

30 35 I do not limit myself to the particular arrangement of the contact rails and shoes above described, nor to the precise wiring shown, nor to the use of any particular materials in the construction and operation of the system.

Having thus described my invention, I claim as new and desire to secure by Letters Patent:

1. The combination of a semaphore arm, 45 contact mechanism controllable by movements thereof, a plurality of separate wires connected with said contact mechanism, a plurality of alarm members mounted within a tower-house and connected with said wires 50 so as to be energized by movements of said semaphore arm, a plurality of alarms carried by a locomotive, and electric mechanism controllable by movements of said locomotive for connecting said alarm members carried 55 by said locomotive with said wire leading to said contact mechanism and for disconnecting the same therefrom.

2. The combination of a semaphore arm, contact mechanism actuated by movements 60 of the same, wires connected with said contact mechanism, alarm mechanism mounted upon a movable locomotive, wires disposed adjacent to the track and adapted to be automatically connected with said alarm mechanism upon said locomotive, other alarm mechanism located in the tower-house, wires connected with said last-mentioned alarm mechanism, said wires adjacent to said track and said wires leading to said tower-house, 70 being connected each in multiple with one of said wires connected with said contact mechanism, and a source of electricity for energizing all of said wires.

In testimony whereof I have signed my 75 name to this specification in the presence of two subscribing witnesses.

ANTHONY A. BARBERA.
